UNITED STATES PATENT OFFICE.

SJUNE SVENSSON, OF HISSMOFORS, KROKOM, SWEDEN.

METHOD OF CHARGING CELLULOSE BOILERS AND THE LIKE AND DEVICE ADAPTED THEREFOR.

Application filed February 8, 1926, Serial No. 86,824, and in Sweden December 11, 1925.

For the charging of cellulose boilers, different methods have been tried, such as stamping, blowing in air et-cetera, in order that the wood chips might be more compact in the boiler than they would be if they only fell down of their own weight.

According to the present invention a jet of steam is used for inserting the wood chips into the boiler. This steam is condensed in the boiler and consequently no suction is required. At the same time that the steam moves the chips, it effects a considerable saving in the time of steaming.

An example of the manner of process will be more closely described in the following with reference to the accompanying drawing, which shows a suitable device for the procedure in Fig. 1 seen from the side and in Fig. 2 seen from above.

An open cylinder 2 is arranged for the insertion of the wood chips into the boiler. The cylinder is provided at the top with a flange 1, which is arranged on some appropriate support to hold up the cylinder in suitable position in relation to the feeding hole of the boiler. An encircling pipe 3 rests on the flange, which pipe is joined to a certain steam source situated outside the boiler. From said pipe 3 six smaller pipes 4, 5 which pass through the flange go downwards, and open out inside the cylinder at different levels. The lower parts of the pipe are bent in the same direction in such a way that the jets of steam are directed slantingly downwards. The pipe, if one so desired it, could naturally be altogether arranged inside the cylinder.

The wood chips fed to the cylinder are

carried by the jets of steam and hurled by these in whirling motion down into the boiler.

The invention is not limited to cellulose boilers but may also be used for other devices for similar purposes.

Having now described my invention, what I claim as new and desire to secure by Letters Patent is:

1. A method for charging cellulose boilers and the like characterized in that the charge is inserted into the boiler by means of steam which is forced into it.

2. A method according to claim 1, characterized in that the charge is inserted into the boiler by means of several jets of steam directed slantingly downwards.

3. A device for charging cellulose boilers and the like consisting of a cylinder adapted to be joined to the boiler, a pipe for supplying steam, and other pipes opening at one end into the cylinder and at the other end communicating with the steam-supplying pipe.

4. A device according to claim 3, characterized thereby, that the pipes open in slanting direction downwards at different levels in the cylinder.

5. A device according to claim 3, characterized in that the cylinder is provided at the top with a flange adapted to carry the cylinder, and that on this flange a steam pipe is arranged from which the pipes opening into the cylinder go.

In witness whereof, I have hereunto signed my name.

SJUNE SVENSSON.
